ANATOMICAL DEMONSTRATING DEVICE

Carl A. Schulz, Glenview, Ill.

Application September 20, 1933, Serial No. 690,222

12 Claims. (Cl. 32—71)

This invention relates in general to an anatomical demonstrating device, but more specifically to a device for use in the demonstration of diseased condition of the mouth, such as pyorrhea, Vincent's angina (commonly known as trench mouth), ulcerated roots, fistulous openings (abscesses), and the like, and one of the objects of the invention is to provide an improved device of this character simulating a portion of the human 10 anatomy, comprising in the present exemplification of the invention, a portion of the mouth, such as the gums, palate and teeth, constructed and arranged in such a manner that when manipulated the course of flow and action of the fluid 15 which is formed and always accumulates under such diseased conditions, may be readily seen and disclosed to the observer.

To the attainment of these ends and the accomplishment of other new and useful objects as will 20 appear, the invention consists in the features of novelty in substantially the construction, combination and arrangement of the several parts hereinafter more fully described and claimed and shown in the accompanying drawing illustrating 25 this invention, and in which

Figure 1 is a side elevation of a device of this character constructed in accordance with the principles of this invention.

Figure 2 is a top plan view of Figure 1. 30 Figure 3 is a longitudinal sectional view taken on line 3—3, Figure 2, showing the parts in normal position.

Figure 4 is a view similar to Figure 3, showing the parts in a position they will assume during 35 demonstration of the device.

Figure 5 is a detail sectional view, on an enlarged scale, taken on line 5—5, Figure 3.

Figures 6, 7 and 8 are modified forms of the invention.

Figure 9 is a view of another form of the invention.

In the present exemplification of this invention, the device will be described and claimed for use in connection with dentistry, but it is to be understood that the invention is not to be limited to that particular art, as the same may be well adapted for use in demonstrating diseased conditions of any of the skeletal pieces of the human body.

Referring more particularly to the drawing the 50 numeral 10 designates generally a body portion which is constructed of any suitable material, but preferably opaque and of resilient material such as rubber or the like, and the material is of such 55 a nature that it will resume its natural condition

or shape after the same or a portion thereof has been distorted.

In the present form of the invention the body portion is in the shape of one of the gums and palate 11 of the human mouth. Teeth 12 simulating the human teeth are arranged within the gum 10 in a manner similar to human teeth and provided in the body portion 10 is a chamber or cavity 13 of any desired size and configuration. Leading from the cavity or chamber 13 are one or more tubes 14 constructed of any desired and suitable material.

One end of these tubes terminates at and opens through the surface of the gum or body portion as at 15, and the inner extremities of the tubes 70 project into the chamber or cavity 13 for a sufficient distance to be at all times submerged in a liquid 16 within the chamber or cavity.

This liquid 16 may be of any suitable color or mixture and is supplied to the chamber or cavity 75 13 preferably through a fill opening 17 having a closure 18, preferably in the form of a headed screw which is threaded into the opening 17. The fill opening is anchored in any desired or suitable manner preferably by means of wings 80 or projections 19 that are embedded in a portion of the body 10. A cap 20 may be provided if desired so as to form a finish for the fill opening.

In the form of the invention shown in Figures 85 3 and 4, one of the tubes 14 is so arranged that its outlet end 15 will be disposed adjacent a cavity 21 in the body in proximity to one of the teeth, while the outlet end of another of the tubes 14 will terminate adjacent the outer face of the body portion remote from the teeth.

Obviously any number of these tubes may be provided if it is desired to use the device for demonstrating diseased condition of a plurality of teeth.

In the form of the invention shown in Figure 95 7, the body portion 10 is provided with a cavity 22 and arranged in the tooth 23 is a channel or passage 24 which has communication with the cavity 22 and opens through the top of the body 10 and in which cavity 22 the liquid 25 is contained.

In the form of the invention shown in Figure 8, a channel or passage 26 is provided in the body portion 10 adjacent the face of the lower portion 105 of the tooth 27, and the channel 26 opens through the top of the body portion 10 adjacent the tooth.

In the form of the invention shown in Figure 6, the tooth 28 is provided with a channel 29 therethrough representing the nerve cell, and in 110

the lower end of the tooth is inserted one end of a tube 30 which is in register with the channel 29. The inner end 31 of the tube 30 projects into the chamber or cavity 13 to be submerged 5 in the liquid 16 within the cavity.

In each form of the invention and in use, the liquid 16 as shown in Figures 3, 4 and 6, and the liquid 25 in the cavities 22 in the form of the invention shown in Figures 7 and 8, is adapted 10 to be forced through the respective passages or channels to the outer surface of the body, and this may be accomplished in one of several ways.

As shown in Figure 4, one of the walls 32 of the chamber 13 may be in the form of a web or of 15 a thickness considerably less than the thickness of the remaining walls so as to allow the same to be easily deflected or distorted when pressure is applied thereto.

The normal position of the form of the invention shown in Figures 3 and 4 is illustrated in 20 Figure 3, and in use the device may be grasped between the thumb and forefinger of the hand, with the forefinger resting against the wall 32 while the thumb rests against the portion 11 of 25 the device, representing the palate. By exerting pressure upon the body portion with the thumb and forefinger the wall 32 will be deflected, with the result that the liquid 16 in the chamber 13 will be forced through the tubular members 14 to be discharged through the ends 30 15 of the tubes. This will demonstrate the action of the fluid or pus formation in the human mouth under a diseased condition of the mouth, as the liquid will be forced through the tubes so that 35 it will have the appearance of oozing or flowing out of the gums at the base or the diseased portion of the tooth, as well as through the gum at points remote from the teeth, according to the 40 number of tubes and the location of such tubes.

40 As soon as pressure of the thumb and forefinger is relieved, the suction created in the chamber 13 will cause the liquid which has been discharged to flow back into the chamber.

45 In this form of the invention, the body portion may be also constructed of such a material and of such resiliency that when the device is resting flat upon a support such as a table or the like, the body portion may be temporarily distorted sufficiently to cause the fluid in the chamber or 50 cavity 13 to be ejected through the tubes 14 by a pressure exerted upon the tips of one or more of the teeth 21.

55 In the form of the invention shown in Figures 7 and 8, the action will be the same as described in connection with Figures 3 and 4, while in the form of the invention shown in Figure 6, the fluid will flow through the tooth 28 under the same action instead of alongside of the tooth as described in connection with the thumb shown in 60 Figures 3, 7 and 8.

65 In the form of the invention shown in Figure 9, there is disclosed a means whereby the action of the fluid in an abscessed condition of the tooth may be readily seen. In this form of the invention the numeral 33 designates the body portion of the device, and 34 designates teeth. One of the teeth is provided with a channel or passage 35 extending therethrough, and in this form of the invention the lower portion of the tooth is removed as at 36, and a cavity 37 with which the channel 35 in the tooth communicates, is arranged at the root of the tooth, the cavity 37 containing liquid and representing an ulcer formed at the base of the tooth. The open side of the 70 channel 35 as well as an open side of the cavity 75

37 is closed by means of a transparent closure 38, preferably in the form of glass secured and held in position with respect to the body 33 in any desired or suitable manner.

80 In this form of the invention when pressure is exerted upon the top of the tooth containing the top of the channel 35, the liquid in the cavity 37 will be forced through the channel 35 and out of the open channel at the top of the tooth. The resiliency of the body portion 33 will permit of such action of the teeth and when pressure of the finger on the tooth is relieved, the inherent resiliency of the body portion 33 will cause the tooth to return to its normal position, and at the same time the liquid which has been forced into the channel 35 will be drawn back into the chamber or cavity 37.

85 With this invention it will be manifest that any diseased condition of the mouth may be readily demonstrated, and while the preferred forms of the invention have been herein shown and described, it is to be understood that various changes may be made in the details of construction and in the combination and arrangement of the several parts, within the scope of the claims, 90 without departing from the spirit of this invention.

95 What is claimed as new is:—

100 1. An anatomical demonstration device of the character described embodying a body simulating a portion of the mouth, and teeth projecting from said body, said body having a cavity therein for containing a liquid, there being one or more openings in the body leading from said cavity through the outer surface of the body, and means whereby the size of the cavity may be reduced to force 110 the liquid therefrom.

115 2. An anatomical demonstration device of the character described comprising a body shaped to simulate a portion of the mouth, and teeth projecting from said body, a cavity in the body for containing a liquid, there being one or more openings leading from said cavity through the outer surface of the body, a portion of said body being 120 resilient whereby upon pressure upon the same liquid will be forced from said cavity through said openings.

125 3. An anatomical demonstration device of the character described comprising a body shaped to simulate a portion of the mouth, and teeth projecting from said body, a cavity in the body for containing a liquid, there being one or more openings leading from said cavity through the outer surface of the body, a portion of said body being resilient whereby upon pressure upon the same 130 liquid will be forced from said cavity through said openings, said liquid being returned to said cavity by suction within the cavity when such pressure is relieved.

135 4. A device for demonstrating the action of pus in a diseased condition of the mouth, comprising a yieldable body simulating a portion of the mouth, teeth arranged in said body, and means within the body for holding a liquid simulating pus, there being one or more openings through which the liquid may pass to the exterior surface of the body when pressure is exerted upon a portion of said body.

140 5. A device for demonstrating the action of pus in a diseased condition of the mouth, comprising a body constructed of material capable of being distorted and having a tendency to return to normal shape, said body simulating a portion of the mouth, teeth arranged in said body, and means within the body for holding a liquid simulating 145

- pus, there being passages whereby the liquid may pass through the body to the exterior surface thereof when pressure is exerted upon a portion of said body.
- 5 6. A device for demonstrating the action of pus in a diseased condition of the mouth, comprising a flexible body simulating a portion of the mouth, teeth arranged in said body, and means within the body for holding a liquid simulating pus, there being openings through which the liquid may pass through the body to the exterior surface thereof when pressure is exerted upon a portion of said body to reduce the size of the liquid holding area, a portion of said body being transparent.
- 10 7. A device for demonstrating the action of pus in a diseased condition of the mouth, comprising a body constructed of material capable of being distorted and having a tendency to return to normal shape, said body simulating a portion of the mouth, teeth arranged in said body, and means within the body for holding a liquid simulating pus, there being openings through which the liquid may pass to the exterior surface thereof when pressure is exerted upon a portion of said body, a portion of said body being transparent.
- 15 8. A device for demonstrating diseased conditions of the mouth, comprising a body shaped to simulate a portion of the mouth, teeth projecting from the body, and means within the body for holding a quantity of liquid, there being openings whereby said liquid may be caused to exude from the said body.
- 20 9. A device for demonstrating diseased condition of the mouth, comprising a body shaped to simulate a portion of the mouth, teeth projecting from the body, and means within the body for holding a quantity of liquid, said body having passages therethrough and being constructed of material adapted to be temporarily distorted to cause
- 25 the liquid to exude therefrom and being of a nature to return to normal after distortion.
10. A device for demonstrating diseased condition of the mouth, comprising a body shaped to simulate a portion of the mouth, teeth projecting from the body, means within the body for holding a quantity of liquid, said body being constructed of material adapted to be temporarily distorted to cause the liquid to exude through passages to the outside thereof and being of a nature to return to normal after distortion, and a transparent area in the said body to permit inspection of the liquid within the body.
- 80 11. A device for demonstrating diseased condition in the human body, comprising a body simulating that portion of the human body which includes the zone of the disease, and means within the second recited body for holding a quantity of liquid, the second said body being constructed of distortable material adapted to return to normal shape after distortion, there being openings whereby upon distortion of such material the liquid will be exuded through the second said body from the interior to the exterior thereof.
- 85 12. A device for demonstrating diseased condition in the human body, comprising a body simulating that portion of the human body which includes the zone of the disease, and means within the body for holding a quantity of liquid, the second said body being constructed of distortable material adapted to return to normal shape after distortion, there being openings whereby upon distortion of such material the liquid will be exuded through the second said body from the interior to the exterior thereof, a portion of the second said body being transparent to permit of inspection of the circulation of the liquid therein.
- 90 100 105 110 115 120 125 130 135 140 145 150
- 40 45 50 55 60 65 70 75
